UNITED STATES PATENT OFFICE.

ROBERT IREDELL, OF AKRON, OHIO, ASSIGNOR TO THE GENERAL TIRE AND RUBBER COMPANY, OF AKRON, OHIO, A CORPORATION OF OHIO.

DESIGN FOR A TIRE TREAD.

Application filed October 3, 1921. Serial No. 505,201. Term of patent 14 years.

To all whom it may concern:

Be it known that I, ROBERT IREDELL, a citizen of the United States, residing at Akron, in the county of Summit and State of Ohio, have invented a new, original, and ornamental Design for a Tire Tread, of which the following is a specification, reference being had to the accompanying drawings, forming a part thereof.

In the drawings, Fig. 1 is a top plan view of a portion of the tire tread. Fig. 2 is a cross section on the line 2—2 of a portion of the tire tread. I claim:

The ornamental design for a tire tread, as shown.

ROBERT IREDELL.
